TREE HOLDER

Filed Oct. 5, 1929

UNITED STATES PATENT OFFICE

JAMES E. DOYLE AND JAMES E. MCWILLIAM, OF WORCESTER, MASSACHUSETTS

TREE HOLDER

Application filed October 5, 1929. Serial No. 397,665.

Our present invention relates to holding devices, and more particularly to an improved tree stand or holder.

In the use of trees as an ornament, and particularly in the use of Christmas trees, an important accessory is the provision of means for not only quickly and accurately placing the Christmas tree in position but also for holding the Christmas tree rigidly in the position decided upon. With the majority of people, a Christmas tree holder is a rather perishable article in that heretofore it has rarely been carried over from one year to the next and this appears to be due primarily to the difficulty experienced and skill required to set the same in position and affix the Christmas tree thereto. Numerous accidents result because of the inability of the average person to rigidly set up a Christmas tree in the usual commercial holder.

A Christmas tree holder, to be successful, should be simple in character and easily set up and adjusted by a relatively unskilled person and as far as we are aware, no such article is at present on the market.

In our present invention we have devised a Christmas tree holder which may be manufactured and sold at a minimum cost and which will receive the ordinary Christmas tree and hold the same rigidly therein with little effort and the Christmas tree holder is of such character as to hold the tree rigidly in the desired position without fastening means of any kind although we find it desirable and as an additional method of safety to provide means for securing the holder or stand to the floor or other base. But one fastening device, however, is necessary although more may be used if desired.

The object of our invention, therefore, is an improved Christmas tree stand or holder.

In the accompanying drawing illustrating a preferred embodiment of our invention,

Fig. 1 is a front elevation;

Fig. 2 is a section on the line 2—2 of Fig. 3;

Fig. 3 is a plan view, and

Fig. 4 is a perspective view.

Referring to the drawings, 10 designates generally an angle supporting member comprised of spaced side plates 11, a bottom plate

12 and a rear plate 13. The plates 11, 12, and 13 are preferably formed of a single stamping and the plate 13 which is normally in a substantially vertical plane, has formed a cup-shaped depression 14 on one face thereof and centrally arranged in such cup-shaped depression 14, which may be part of a sphere, is a perforation 15 for a purpose to be herein-after described. The plates 11, 12, and 13 form a unitary structure which is secured to 55 parallelly arranged and vertically located bars 16 by rivets 17 or other suitable fastenings which pass through the plates 11.

The plate 12, which may be designated the bottom plate, is arranged parallel with the 60 floor and is spaced a slight distance therefrom, as will be obvious from an inspection of Fig. 2. This bottom plate 12 is provided with a centrally arranged perforation 18 through which may pass a screw 19 to enter 65 the floor on which the bars 16 rest. The bars 16 may be of any length desired and the ends are formed into ogee sections. Preferably we employ the ogee end although any other end desired may be utilized.

Fitting within the spherical depression 14 is a segment of a sphere 21 provided at diametrically arranged points with forked members 22 and the segment of a sphere 21 is provided with a hole or perforation 23 of 70 greater area than the hole 15 in the segmental projection 14. The spherical section 21 is in frictional engagement with the spherical depression 14 and it will be obvious that the forked ends 22 of such spherical projection 21 75 may be moved to any position with relation to the spherical depression 14 within the limits of the structure. Preferably the forked ends 22 are in vertical alignment with respect to each other and are adapted, therefore, to engage with the hole of the Christmas tree or other structures 24. Passing through the holes 15 and 23 is a threaded screw 25 provided on its outer end with an operating handle 26 and by reference to Fig. 2 it will 80 be noted that such screw 25 screws into the hole or body of the Christmas tree 24 and when the screw 25 is screwed into the hole or body 24 until the operating handle 26 engages with the outer face of the spherical 85

projection 14, the bole or body 24 of the tree forces the spherical projection 21 into close engagement with the inner face of the projection 14 and holds the same rigidly in position.

5 It will be obvious that regardless of the difference in diameter of the bole of the tree 24 as far as the engagement of the upper forked member 22 and the lower forked member 22 is concerned, that the engaging screw 25 will still be able to draw the spherical projection 14 into close engagement with the inner face of the spherical projection 14 and by this means the Christmas tree 24 will be 15 held rigidly in position in the device.

While we have shown and described our preferred embodiment as being made of sheet material formed into a unitary structure, yet it is obvious that we are not limited to such 20 a construction as the plates 11, 12, 13 and 14 may be made separate and fastened together in any approved manner and may be sheet metal or machined, as desired.

Having thus described our invention, what 25 we claim as new is:

1. In a device of the kind described, the combination of a base, a tree support mounted thereon, a bearing surface formed on said tree support, a tree engaging member associated with the bearing member, and means for engaging the tree and drawing the tree engaging member into close association with the bearing member.

2. In a device of the kind described, the 35 combination of a pair of parallelly arranged supporting bars, a tree holding base secured to said bars and holding the bars separated from each other, a vertically arranged plate forming part of said tree holding plate, a 40 bearing formed in said vertical plate, a second bearing member associated with the first bearing member, tree engaging points formed integrally with said second bearing member, and means associated with said bearing members and engaging a tree trunk to force the bearing members into locking position with respect to each other.

3. In a device of the kind described, the combination of a base, a pair of parallelly 50 arranged supporting bars secured to the bottom of said base, a spherical bearing member carried by said base, a co-operating spherical bearing member associated with the first said bearing member and provided with vertically arranged tree engaging points, and a screw threaded member associated with said spherical bearing members and adapted to engage with a tree trunk and draw the spherical bearing members into locking engagement with each other.

4. In a device of the kind described, the combination of a base, a tree support mounted thereon, a bearing surface formed on said tree support, a tree engaging member associated with the bearing member, said tree

engaging member being provided with a bearing surface co-operating with the bearing surface on the tree support, and means for engaging the tree and drawing the bearing surfaces into frictional contact with each other.

5. In a device of the kind described, the combination of a base, a tree support mounted thereon, a spherical bearing surface mounted on said tree support, a tree engaging member provided with a spherical bearing surface associated with the spherical bearing surface on the tree support, and means for engaging the tree and drawing the spherical bearing surfaces into frictional contact with each other, whereby the tree engaging member is locked against movement to support the tree rigidly in position.

In testimony whereof, we have signed our names to this specification.

JAMES E. DOYLE.

JAMES E. McWILLIAM.
